UNITED STATES PATENT OFFICE.

GEORGE HOLT FRASER, OF BROOKLYN, NEW YORK.

PULVERIZING MILL.

Application filed April 30, 1918, Serial No. 231,599. Renewed September 25, 1923.

To all whom it may concern:

Be it known that I, GEORGE HOLT FRASER, a citizen of the United States, residing in the borough of Brooklyn, county of Kings, city 5 and State of New York, United States of America, have invented certain new and useful Improvements in Pulverizing Mills, being a continuation in part of my application Serial No. 858,797, filed August 27, 10 1914, forfeited and renewed December 18, 1916, bearing Serial No. 267,401, and which has eventuated into Patent No. 1,317,014, dated September 23, 1919, of which the following is a specification.

15 This invention relates to apparatus for pulverizing materials and for separating the fine material by means of a fluid current, and aims to provide certain improvements therein.

20 Heretofore it has been common to pulverize material by means of balls or rollers revolved within an annular die against the inner periphery of which they act centrifugally to crush the material, the fine particles being carried out by an air current and coarse particles being intercepted by a screen surrounding the crushing chamber.

25 The present invention relates especially to pulverizers utilizing some of these principles of operation, and aims to provide improvements in pulverizers generally but especially applicable to those of this general type.

30 To this end in carrying out the preferred form of my present improvements I provide a casing, pulverizing elements comprising either a revolving or stationary die disposed either vertically or horizontally in the latter, rotatable balls or rolls movably carried, which if the die revolves will be carried by non-rotative movable carriers, and if the die is stationary will be carried by revolving carriers or pushers, and in either case there will be an aperture of current inlet centrally of the rock pan or crushing chamber below or inwardly of the die, and a web above, leaving a passage between for the returning air, which will jet through this passage toward the die, blowing the 45 material into the latter and the fines upwardly and out, and I provide one or more sets of annular troughs in the path of the

air current and above the crushing elements so that this current may flow out between the annular troughs of the primary set and 55 preferably also a secondary selecting set, which troughs afford downward outlets through which large particles extracted by them may fall back into the pan, and afford sinuous current passages through which the 60 current may flow outwardly to float out. material fine enough to be carried through these passages, and I provide an outer current passage descending outside of said troughs, and a lower separating chamber for 65 receiving the dust laden air current therefrom and separating its dust, and I provide extracting means for intercepting or filtering floating particles from the air current returning to the pulverizing chamber 70 so that it may be clean and continuously reused, and I provide a rotary fan, preferably an outside blower exerting the suction within the filter so as to produce a pressure vacuum or rarefaction in the outer 75 part of the casing surrounding said parts, to draw the fine material upward by suction and lift it out of the die by the blast, so that the outermost chamber surrounding 80 said elements has a partial vacuum for insuring a more even and moderate current flowing through the various passages and avoiding danger of out-blowing dust, and to produce a tendency for the dust and air to enter rather than escape from the periphery of the casing; and I provide certain 85 other features of improvement all of which will be more fully hereinafter set forth with reference to the accompanying drawings; 90 in which,

Fig. 1 is a vertical axial section showing the preferred form of my invention as applied to a pulverizer having a die fixed in a horizontal plane and an outside blower;

Fig. 2 is a horizontal section thereof cut 95 on the planes of the lines 2—2 in Fig. 1, and

Fig. 3 is a horizontal section thereof cut on the planes of the lines 3—3 of Fig. 1.

Fig. 4 is a vertical axial section showing a modified form of my invention having an 100 inside blower separably coupled to a shaft differentially driven through the main shaft for slow speed and separably coupled to an inside motor for higher speed.

Referring to the drawings let A indicate the main frame or casing of a pulverizer, B the inlet thereof, C the outlet thereof, D the crushing chamber thereof, E the fine chamber thereof, F the fan or blower thereof, and G the driving means thereof.

These parts may be of any suitable construction or disposition sufficing to pulverize the material, to generate the necessary current to float out the fine product and discharge the latter. As shown the frame or casing comprises a base H which is preferably a hollow annular or cup shaped casting adapted to rest on a support and to support or carry the other parts of the apparatus, a top frame I, an upper shell J, and a lower shell K, which parts enclose the crushing chamber D, crushing elements C, and fine chamber E.

The crushing elements shown comprise movable and revolving rolls L within and acting outwardly toward the inner crushing face of a fixed die M removably mounted in the base H.

The driving mechanism shown comprises a revolving carrier N connected by a shaft O with suitable driving gear as the belt pulley G for example.

The fine chamber E is shown as an annular chamber below and surrounding the feed chamber and communicating therewith through an annular outer or egress passage P and an inner or ingress passage Q, which passages afford an endless current passage through the crushing chamber, to the fine chamber, and from the latter back into the crushing chamber to permit a current to flow continuously through these to float out fines from the crushing chamber to the fine chamber and return the current to the latter.

According to one feature of improvement I provide an annular interceptor R surrounding the crushing chamber and intersecting the current passage P therefrom, and preferably consisting of a plurality of loosely mounted or removable annular superposed reversely inclined baffles or members a and b spaced apart to afford between them sinuous outwardly extending current passages c and having lower outlets d affording downward material outlets for large particles precipitated between them which serve to cause lifted material to descend in an annular path or blanket across the outflowing current so that this may extract fine material therefrom while coarse material will be intercepted and descend, which outlets communicate with the crushing chamber for returning such particles to the crushing elements, while the current passages communicate with the egress passage for discharging outflowing current thereto.

These baffles prevent large pieces passing to the fine chamber, permitting free flow of current, and are not subject to the danger

of puncture, clogging or wear, incident to screens. They are disposed to avoid a direct path for the outlet of large pieces projecting from any direction and to intercept and return these for crushing, and serve to regulate the fineness of discharge to that which can float through the passages between them.

According to another feature of the preferred form of my invention I provide succeeding the baffles R annular selecting means S, preferably consisting of a second series of reversely inclined members or plates e and f superposed and spaced apart to afford between them sinuous current passages g and lower outlets h, which passages receive outflowing current from the passages c and select therefrom large particles which descend through the outlets h, which communicate with and return them to the crushing chamber. This secondary or selecting element S affords assurance that no material too large to float through it shall reach the fine chamber.

According to another feature of improvement I preferably provide extracting means T between the fine chamber and the return conduit and the ingress passage Q for intercepting fine material floating in the return current. Preferably this is accomplished by providing two series of hollow troughs i spaced apart and affording two annular foraminous walls one within the other for the inner side of the fine chamber, which troughs afford sinuous passages j between them for the inflowing current from the chamber and are staggered so that the concave side of the inner troughs will be opposite the space between the outer troughs. These troughs extend vertically, and are preferably slightly inclined toward the approaching current at their lower parts, affording vertically elongated current passages between their edges, and affording vertically elongated air passages or dead spaces opposite their concavities in which fine particles may settle so that these can slide down their outer faces and be precipitated in the fine chamber. The return passage from the fine chamber is preferably an annular inwardly extending and contracting passage the bottom of which is afforded by an outwardly inclined ring or cone k below and spaced apart from the bottom wall l of the crushing chamber to afford a horizontally inwardly extending annular space or conduit m under this, through which the return current flows from the fine chamber inwardly to again reach the crushing chamber, and between which and the latter the return current passage is preferably closed from communication with the fine chamber, receiving return current from the filter and delivering it through the ingress passage Q to the crushing chamber, either directly if

the current generating means is directly above the latter, or through such means if these are below or without such chamber.

According to another feature of improvement I preferably provide current generating means below the crushing chamber, and which may be within, inwardly of or below the fine chamber, and driven independently of or be concentric with or driven by or through the driver G, but which preferably are disposed exteriorly of the main casing and connected therewith by closed suction and exhaust passages constituting with the blower itself a part of the endless current passage of the pulverizer. This is preferably accomplished by mounting the blower F under and at the side of the main casing and connecting its suction pipe n with the passage m through the medium of an annular equalizing chamber U from which the suction pipe leads tangentially so that the exhausting current will be whirled centrifugally to insure a uniform suction all around the passage m; and by connecting the blast pipe o to the blower with a blast or pressure chamber V into the cylindrical wall of which it discharges tangentially to insure centrifugal whirling of the current around the inner wall p of the blast chamber so that the pressure will equalize therein and flow equally upward below the lower edge of this wall through the central opening q therein and rise through the chamber r within the cones p and s to the ingress passage Q. I prefer to regulate the current by a butterfly valve t, and to drive the blower and crushing elements with relative adjustability simultaneously from the main drive shaft u' of the apparatus so that these elements will operate reciprocally and in unison to provide for variations in speed or conditions regardless of their independent adjustment from time to time.

When the blower is placed within the main casing it will preferably operate on a vertical axis, being mounted in the chamber r, and being a barrel blower having a closed upper head and an annular open bottom suction communicating with the passage q to receive current therefrom and blow it into the chamber from which it will rise to the passage Q. In such case it will be driven by a motor below, or by a shaft rising to or through the shaft O and driven by a separate gear from the top gear thereof with an intermediate idler to multiply blower speed, as seen in Fig. 4.

According to another feature of improvement the lower part of the casing is cut away, recessed, divided, or bifurcated, and affords separate outlets C¹ and an intermediate way or passage W² for access to or removal of the internal parts, through which the conduits n and o pass and in which the

blower F may be mounted, and as shown the lower casing K comprises a cylindrical outer wall u suspended from the under side of the base H, and carrying a plurality of flat segments or bottoms v which meet at 70 their edges and afford removable bottom plates for the chamber E, and through which the separate outlets C open for discharging dust into a transverse diametrically extending conveyor W' which converges their product, and the cylindrical wall w of the suction and blast chambers U and V, and the bottom conical wall x of the latter, are disposed in the space between these outlets C below bottoms v and accessible therein, and the removable door or bottom y, comprising a removably mounted reverse cone closing the bottom of the cone x, and all these parts are separably suspended from the base and from each other by 80 bolts z.

According to another feature of improvement the feed inlet B comprises an annular hopper discharging centrally of the feed chamber, and a centrifugal feeder X is provided which is removably and adjustably mounted on the carrier N and throws the material over the rolls on to an annular shelf or feeder Y surrounding the ring so that there may rest on this a mass of material to receive the impact of new feed and thus prevent wear and the material may fall by gravity annularly of the face of the ring in front of the approaching rolls.

According to another feature of improvement the rolls are pivotally or swingingly mounted on the carrier by swinging members Z and each pivoted to the carrier and each carrying a roll so that the latter can swing in and out as it works. Preferably the carrier has arms a¹ having pivotal sockets b¹ (shown in dotted lines in Fig. 1) in which removably drop pins c¹ on the links Z which rest on top of the arms and have downwardly extending parts which pass in front of and beneath the rolls and have upwardly extending tubular pins e¹ receiving bearing studs f¹ on the rolls for rotatively carrying the latter. The front edge g¹ of each link preferably serves as a plow or lifter for scraping material from the bottom of the rock pan h¹ and throwing it up on the inner face of the ring in front of the approaching roll and thus any roll may be lifted off and any link may be lifted out without disturbing other parts after the top has been opened, as the feeder X and carrier N are proportioned to afford clearance for ingress or egress of the convex face of the roll passing the concave face of the ring. Between the arms a¹ the carrier has roll sockets z¹ and its lower side is concave and provided with a lip j¹ between which and the upturned lip k¹ of the base is afforded an annular part l¹ of the ingress passage Q.

My invention preferably also provides for supplementing centrifugal force as a crushing element by applying outward pressure to the crushing rolls and utilizing the reaction of one roll against another, which is preferably done by pressing means m^1 intermediate of the members Z , acting outwardly toward these and movable radially thereof to equalize the stress between them and transmit the thrust of one to another. This may be accomplished in any suitable way, but I prefer to use two loose radially and axially movable rings n^1 concentric of shaft O below the carrier N , adjustably and 15 yieldingly pressed toward each other by springs o^1 adjusted by a reverse tension screw p^1 , and acting divergently toward the carriers through compression toggles q^1 pivotally engaging rockers t^1 on each and 20 pressed from each other by a reverse spring s^1 to retire the carriers when pressure is released, which parts revolve with the carrier in the construction shown, and follow the movement of the rolls.

25 In operation with the construction set forth feed will enter annularly and be distributed above the crushing elements and below the selecting elements, affording its own wear cushion as it is deposited in an 30 annular mass exteriorly of the crushing face, and will fall slowly within the latter, so that only material escaping crushing will descend into the pan and have to be plowed up therefrom by the auxiliary plows r^1 on the under-side of the arms a^1 . The outward 35 air current will lift and blow fine material from the pan upwardly in front of the rolls, and will lift pulverized material from the crushing chamber to within the selectors, in 40 floating between which large particles will be extracted and returned for crushing and material remaining in the current will descend with it to the fine chamber where it will precipitate and fall to the outlets, and 45 as the current returns from the fine chamber particles still floating in it will be filtered out by and slide down the filter tubes to extract all the fines and return the current comparatively clean to the blower. The 50 concentric arrangement of passages, and centrifugal suction and discharge connections between these and the blower will equalize current pressures peripherally of the parts, and the connection of the suction side of 55 the blower with the outer chambers and the blast side with the inner chambers will afford a rarefaction in the former compared to the pressure in the latter which 60 will tend to avoid escape of dust.

65 The several rolls can be removed individually, their swinging links can be removed separately, but these and the carrier which is removably mounted can be removed together, thus exposing the base for lifting out the ring after the top has been taken off.

The lower casing and parts may be dropped from the base without disturbing the superstructure, or either the outer or inner of these may be separately removed.

Pressure will be transmitted from one roll 70 to the others, and the pressure exerted by these can be adjusted or initially set at sufficient degree to effect crushing without requiring such speed as would be requisite to do this by centrifugal force. Pressure will 75 be equalized between the rolls and thus will be transmitted from one to another, thus relieving the driving parts and fixed bearings from strain and utilizing the internal force as crushing pressure. 80

It will be seen that my invention provides improvements which can be readily and advantageously availed of in whole or in part, and it will be understood that the invention is not limited to the particular details of 85 construction, arrangement, combination, or use, nor to use with the particular type of pulverizer, set forth as embodying the preferred form of this invention, since it can be employed in whole or in part as circumstances, or the judgment of those skilled 90 in the art, may dictate, without departing from the spirit of the invention.

What I claim is:

1. In combination, a pulverizer, a main 95 frame or casing, a plurality of annular deflectors within said casing, means exhausting air from said casing outwardly of said deflectors, means filtering such air, and means returning the air inwardly of said 100 pulverizer into said casing inwardly of said deflector.

2. In combination, a pulverizer comprising an annular die having an internal crushing face, one or more pulverizing rolls co-operating with said die, means for revolving one of said parts, an annular passage inwardly of said die communicating through the latter, an annular passage outwardly of 110 said die, a foraminous wall, and means causing a fluid current to travel through said die within said foraminous wall, through the latter, and descend exteriorly of said die, and return beneath and through the 115 central part of said die.

3. In combination, a casing enclosing an outer fine chamber, an inner receptacle within said casing affording a crushing chamber and having upper and lower openings respectively above and below it and communicating with said outer chamber, crushing elements in said crushing chamber, means affording an endless current passage connecting said upper and lower openings and including and communicating through said 120 chambers, and means for causing a fluid current to flow through said passage disposed therein to produce a rarefaction in said outer chamber and a pressure in said inner chamber. 125

4. In combination, a casing enclosing an outer fine chamber, an inner receptacle within said casing affording a crushing chamber and having upper and lower openings 5 communicating with said outer chamber, crushing elements in said crushing chamber, means affording an endless current passage communicating through said chambers, means for causing a fluid current to flow 10 through said passage, and reversely inclined baffles in the path of such current affording sinuous current passages and precipitate outlets below an intermediate portion of such passages.
5. In combination, a casing enclosing an outer fine chamber, an inner receptacle within said casing affording a crushing chamber and having upper and lower openings communicating with said outer chamber, crushing 20 elements in said crushing chamber, means affording an endless current passage communicating through said chambers, means for causing a fluid current to flow through said passage, and filtering means 25 in the path of such current for extracting floating particles therefrom.
6. In combination, a casing enclosing an outer fine chamber, an inner receptacle within said casing affording a crushing chamber 30 and having upper and lower openings communicating with said outer chamber, crushing elements in said crushing chamber, means affording an endless current passage communicating through said chambers, 35 means for causing a fluid current to flow through said passage, means affording a foraminous wall between said upper opening and said outer chamber for intercepting large particles moving toward the latter, 40 and filtering means between said outer chamber and said lower opening for intercepting fine particles floating in such current toward the latter.
7. In combination, a casing enclosing an outer suction chamber, an inner receptacle 45 affording a crushing chamber and having upper and lower openings communicating with said suction chamber, crushing elements in said crushing chamber, means affording an endless current passage communicating through and between said chambers comprising a tangential suction conduit 50 communicating with said suction chamber, an annular blast chamber communicating with said crushing chamber, a tangential blast conduit communicating with said blast chamber, and means for causing a fluid current to flow through said passage.
8. In combination, a casing enclosing an outer chamber, an inner receptacle in said 60 casing affording a crushing chamber and having an upper opening communicating with said outer chamber, crushing elements in said crushing chamber, an annular revolving feeder below said upper opening and 65 above said crushing elements for feeding material to be crushed into said crushing chamber, and means for causing a fluid current to flow from said crushing chamber through said opening and into said outer 70 chamber.
9. In combination, a casing enclosing an outer chamber, an inner receptacle in said casing affording a crushing chamber and having an upper opening communicating 75 with said outer chamber, crushing elements in said crushing chamber, an annular revolving feeder above said crushing elements for feeding material to be crushed into said crushing chamber, means affording an annular shelf below said upper opening and around said elements for receiving such material from said feeder and feeding it to such elements, and means for causing a fluid current to flow from said crushing chamber 80 through to said opening to said outer chamber.
10. In combination, a casing enclosing an outer chamber, an inner receptacle in said casing affording a crushing chamber and 85 having upper and lower openings communicating with said outer chamber, crushing elements in said inner chamber, and means below said crushing elements for causing a fluid current to flow through said crushing chamber and upper opening into said outer chamber 90 and return through said lower opening.
11. In combination, a casing enclosing an outer chamber, an inner receptacle in said 95 casing affording a crushing chamber and having upper and lower openings communicating with said outer chamber, crushing elements in said inner chamber, and means without said casing for causing a fluid current to flow through said crushing chamber and upper opening into said outer chamber 100 and return through said lower opening.
12. In combination, a casing enclosing an outer chamber, an inner receptacle affording 105 a crushing chamber having an upper opening communicating with said outer chamber, crushing elements revolving in a horizontal plane within said crushing chamber, means for causing a fluid current to flow from said crushing chamber through said opening to said outer chamber, and means for intercepting large particles floating in such current comprising reversely inclined annular baffles 110 disposed in the path of such current above and inwardly of said elements affording a sinuous outward passage for such current and affording beneath said passage and above and inwardly of said elements precipitate outlets for refeeding intercepted particles to such elements.
13. In combination, a casing enclosing an outer chamber, an inner receptacle within 115 said casing affording a crushing chamber and having an opening communicating with 120

- 5 said outer chamber, crushing elements in said crushing chamber, means for causing a fluid current to flow from said crushing chamber and through said opening between 5 said chambers, and means in the path of such current for intercepting solid particles in such current comprising vertically extending faces in and across and extending below the path of such current affording 10 downward ways for conducting out of the zone of such current intercepted particles and affording intermediate of such ways and in the path of such current apertures affording 15 passages for such current.
14. In combination, a casing affording a crushing chamber and a fine chamber, and an endless passage communicating through said chambers, crushing elements in said crushing chamber, oppositely inclined 20 spaced means affording a sinuous current passage above said crushing chamber and affording downward material outlets discharging above said crushing elements, and means for causing a fluid current to traverse 25 said passages.
15. In combination, a casing affording a crushing chamber, a crushing fine chamber, and an endless passage communicating through said chambers, crushing elements in 30 said crushing chamber, and means below said crushing chamber and in said passage between said fine chamber and said crushing chamber for receiving current from the former and extracting material floating in 35 said current returning to said crushing chamber.
16. In combination, a casing affording a crushing chamber, a fine chamber, and a passage communicating between said chambers, 40 in combination with a plurality of crushing elements in said crushing chamber, means intermediate of said elements for transmitting the inner thrust of one to another, and means affording a continuous passage 45 through said chambers intermediate of said thrust means.
17. In combination, a casing affording a crushing chamber and a fine chamber, crushing elements in said crushing chamber, a 50 blower exterior of said casing, and means affording an endless passage through said blower communicating with said crushing chamber below and inwardly of said elements and communicating with said fine 55 chamber.
18. In combination, a casing affording a crushing chamber and a fine chamber, crushing elements in said crushing chamber, a blower below said crushing chamber, and 60 means affording a continuous passage communicating through said crushing and fine chambers and said blower.
19. In combination, a casing affording a crushing chamber and a fine chamber having 65 a central lower recess, crushing elements in said crushing chamber, suction and blast chambers inwardly of said fine chamber and disposed within said recess, and means affording a continuous passage through said chambers. 70
20. In combination, a casing affording a crushing chamber, a stationary annular crushing die mounted in a horizontal plane therein, a plurality of movable and rotatable crushing rolls within and eccentric of said die, a revoluble carrier for said rolls, revolving in a horizontal plane and means pivoted to said carrier on a vertical axis and swinging horizontally pivotally sustaining said rolls from said carrier. 75
21. In combination, a casing affording a crushing chamber, a fine chamber, and an endless passage communicating through said chambers, crushing elements in said crushing chamber, a blower in said passage for causing a current therethrough, and means differentially driving said elements and said blower from a common source of power. 80
22. In combination, a horizontal annular die having an internal crushing face, a rotatable crushing roll within and eccentric of said die and having a peripheral crushing face reciprocal to the inner face of said die, means for revolving one of said parts, a movable carrier on which said roll is rotatably mounted, and means for holding said roll toward said die comprising yielding means acting reversely divergently outwardly against the inner side of said carrier. 85
23. In combination, a horizontal annular die having an internal crushing face, a rotatable crushing roll within and eccentric of said die and having a peripheral crushing face reciprocal to the inner face of said die, means for revolving one of said parts, a movable carrier on which said roll is rotatably mounted, and means for holding said roll toward said die comprising a spring reacting axially of said die and means inwardly of and acting outwardly against said carrier for transmitting the stress of said 90 spring to the latter.
24. In combination, an annular die having an internal crushing face, a rotatable roll within and eccentric of said die, and having a peripheral crushing face reciprocal to the inner face of said die, means for revolving one of said parts, a movable carrier on which said roll is rotatably mounted, and means for holding said roll toward said die comprising differently acting springs inwardly of said roll and means transmitting the stress of both said springs to said carrier. 105
25. In combination, an annular die having an internal crushing face, a rotatable roll within and eccentric of said die and having a peripheral crushing face reciprocal to the inner face of said die, means for revolving one of said parts, a movable carrier on which said roll is mounted, and 110

means for pressing said roll toward said die comprising a spring inwardly of said roll acting on said carrier to press said roll outwardly and means for moving said carrier inwardly to retire said roll.

26. In combination, an annular crushing die having an internal crushing face, movable and rotatable crushing rolls within and eccentric of said die and each having a peripheral crushing face reciprocal to the inner face of said die, means for revolving one of said parts, movable carriers for said rolls respectively, a support for said carriers, and means intermediate of said rolls acting 10 against said carriers for transmitting the inward stress of one to another.

27. In combination, an annular crushing die having an internal crushing face, rotatable crushing rolls within and eccentric of 20 said die, and each having a peripheral crushing face reciprocal to the inner face of said die, means for revolving one of said parts, a rotatable holder for said rolls, and means revolving with and movable relatively to said holder communicating between two of said rolls for transmitting the inward stress of one to another.

28. In combination, an annular crushing die having an internal crushing face, movable and rotatable crushing rolls within and eccentric of said die, each having a peripheral crushing face reciprocal to the inner face of said die, means for revolving one of said parts, and means for pressing said rolls 30 outwardly comprising reversely acting springs intermediate of said rolls and a spring resisting said springs.

29. In combination, an annular crushing die having an internal crushing face, a rotatable crushing roll within and eccentric of said die and having a peripheral crushing face reciprocal to the inner face of said die, means for revolving one of said parts, movable means on which said roll is rotatably 45 mounted, movable holding means for holding said roll toward the inner face of said die to resist a pressure therefrom, and sliding means on which said pressing means are mounted.

30. In combination, an annular crushing die having an internal crushing face, a rotatable crushing roll within and eccentric of said die and having a peripheral crushing face reciprocal to the inner face of said die, 55 means for revolving one of said parts, movable means on which said roll is rotatably mounted, oppositely inclined holding means for holding said roll outwardly toward the inner face of said die to resist a crushing pressure therefrom, sliding means on which said inclined means are movably mounted respectively, and a spring acting to press said sliding means from one another.

31. In combination, an annular crushing 60 die having an internal crushing face, a ro-

tatable crushing roll within and eccentric of said die and having a peripheral crushing face reciprocal to the inner face of said die, means for revolving one of said parts, movable means on which said roll is rotatably mounted, oppositely inclined holding means for holding said roll outwardly toward the inner face of said die to resist a crushing pressure therefrom, sliding means on which said inclined means are movably mounted respectively, and a spring acting to press said sliding means toward one another.

32. In combination, an annular crushing die having an internal crushing face, a rotatable crushing roll within and eccentric of said die and having a peripheral crushing face reciprocal to the inner face of said die, means for revolving one of said parts, movable means on which said roll is rotatably mounted, horizontally acting vertically adjustable inclined holding means for holding said roll outwardly toward the inner face of said die to resist a crushing pressure therefrom, and vertical adjusting means for 80 vertically adjusting said holding means.

33. In combination, an annular crushing die having an internal crushing face, a rotatable crushing roll within and eccentric of said die and having a peripheral crushing face reciprocal to the inner face of said die, means for revolving one of said parts, rotative means on which said roll is rotatably mounted, pressing means for pressing said roll outwardly toward the inner face of said die to resist a crushing pressure therefrom, a casing enclosing said parts, and means without said casing for adjusting said pressing means.

34. In combination, an annular crushing die having an internal crushing face, a rotatable crushing roll within and eccentric of said die and having a peripheral crushing face reciprocal to the inner face of said die, means for revolving one of said parts, rotative means on which said roll is rotatably mounted, pressing means for pressing said roll outwardly toward the inner face of said die to resist a crushing pressure therefrom, a casing enclosing said parts, and means 105 concentric of said rotative means and without said casing for adjusting said pressing means during rotation of said rotative means.

35. In combination, an annular crushing die having an internal crushing face, a plurality of movable and rotatable crushing rolls within and eccentric of said die and each having a peripheral crushing face reciprocal to the inner face of said die, means for revolving one of said parts, movable means on which said rolls are rotatably mounted respectively, rocking links intermediate of and acting on said movable means respectively to hold said rolls out- 120 125 130

wardly to resist a crushing pressure from the inner face of said die and having adjacent inner ends, a movable seat member intermediate of and sustaining the adjacent inner ends of said links, and means for moving said seat member to rock said links.

In witness whereof, I have hereunto

signed my name in the presence of two subscribing witnesses.

GEORGE HOLT FRASER.
